ABRADING ARTICLE

Willard K. Carter, Columbus, Ohio

Application April 5, 1954, Serial No. 420,897

5 Claims. (Cl. 51—204)

This invention relates to abrading articles. In general, 15 the invention comprises an abrading article formed from a multicellular ceramic product provided with flexible reinforcement.

It has been found that multicellular products, for example, such as disclosed in United States Patent No. 1,945,052; No. 2,156,457 and No. 2,337,672, and known under the trade name of Foamglas, can be used for abrading operations. These products have a great number of adjacent cells, usually devoid of communication with each other, which are extremely fragile and easily shattered. When broken the cell walls have value as an abrasive through the utilization of work surfaces formed from the sharp projecting residues of attached but broken and shattered cell walls. The cell wall shattering and breakage to produce a desired abrasive plane or contoured work surface may be obtained by sawing, cutting, or rubbing.

The abrasion produced with these cellular structures results from the cutting action of the broken and shattered cell walls which remain attached to the abrading article. Abrasion is also produced from the cutting action of detached and broken-off particles of cell walls which are subject to progressive comminution as they move about upon the work piece. The detached particles are thus capable of producing smoothing of greater degree as 40 comminution progresses.

One of the objects of the invention is to provide an abrading article of the type described having a flexible reinforcement. This feature of the invention provides for strengthening the structure generally and for maintaining broken cell walls in position to be most effective in abrading operations.

It is also an object of this invention to provide a coating substance forming a fringe which extends around the work surface of the abrading article. This fringe provides for holding debris from broken cell walls and cuttings in contact with the work surface.

One of the advantages of using a cellular ceramic product for abrading purposes is derived from the ability to remove clogging debris from the glassy smooth interiors of the partially hemispherically shaped cell portions forming the cutting surface. The cutting surface may be cleaned simply by tapping or jarring the abrading article while the clogged surface is faced downward so that debris is free to drop away. This allows complete utilization of the abrading article without regard to the surface clogging which limits the usage range of paper coated abrasives. However, in cleaning, the fragility of the structure and the thinness of the cell walls present a disadvantage. The tapping or jarring necessary to free the debris from the work surface requires striking the structure upon an edge and this results in breaking away corner areas or other surface portions which otherwise could have been used for abrading purposes. In accordance therewith, it is another object of the invention to provide a cushioned surface or edge for striking the structure so that it can be

2

jarred or tapped to clean away the debris without causing excessive breaking of the surface structure.

It has been found that these cellular ceramic abrasives are unique in that they have an "eraserlike" wearing action. Thus, starting with an abrading surface of sharp, thin, broken cell walls, as work is accomplished by movement and pressure, the original sharp walls break and new underlaying walls are shattered and exposed. An abrading article thus formed from a suitable cellular ceramic structure is usable throughout its entire volume providing the structure can be held in such a manner as to permit use either manually or by means of fixtures or attachments. Accordingly, a specific object of the invention resides in providing a surface for a cellular ceramic abrading article, which the operator can grasp manually without injury from the sharp edges of the broken cell walls, or which can be held by means of fixtures or attachments without breaking away the structure and diminishing the cross section.

Additional objects, advantages and features of the invention will be apparent from the following description, the appended claims and the accompanying drawings.

Referring further to the drawings, wherein a preferred embodiment only of the invention is shown:

Fig. 1 is a perspective view of an abrading article in block form incorporating the present invention and showing one end, side and bottom thereof;

Fig. 2 is a vertical sectional view through one end of an abrading article, such as shown in Fig. 1, on a work piece;

Fig. 3 is a partial, vertical sectional view of a corner portion of the abrading article of Fig. 2 illustrating its appearance after considerable use and the action of the fringe in collecting and holding debris and cuttings under the work surface; and

Fig. 4 is a perspective view illustrating how an abrading article of the type shown in Fig. 1 is applied to a work piece by the operator.

In the following specification and in the accompanying drawings a specific embodiment of the invention is disclosed and this embodiment is described in detail. However, it is to be understood nevertheless that the primary purpose of illustrating the invention by reference to a specific form thereof and by the employment of detailed language herein is to facilitate an understanding of the principles underlying the invention, and that the scope of the invention is not intended to be limited thereby.

Fig. 1 discloses an abrading article formed from a cellular ceramic structure, indicated generally at 10, such as described in the patents previously referred to herein. This structure 10, which is in the form of a rectangular block, has substantially vertically extending and oppositely disposed sides and end walls 11 and 12. The top surface of the block shown is indicated at 14 and the bottom, which is designated as the work surface, is indicated at 15. It is to be understood that the abrading article may be formed into any other desired shape and that the work areas may be contoured to provide an abrasive surface corresponding to the shape of the article to be finished.

In the preferred form of the invention, the abrading article is coated with a reinforcing substance indicated generally at 16. Referring to Fig. 1, for example, the structure would be coated on all surfaces except the work surface 15 which would remain free of the coating. It is to be understood, however, that for the purposes of this invention it is immaterial whether the abrading article, whatever shape it may be, is coated completely and then the coating removed from an area to expose a work surface or whether the work surface is not coated

at all when the coating is applied to the remaining surfaces.

The preferred coating is flexible to the degree that isolated sheets can be bent or rolled. The coating is sufficiently tough so that when applied to the cellular structure, by either spraying, brushing or dipping processes, the coated structure can be sawed or cut without tearing or rupturing the coating except at the point of tooling. The coating becomes a flexible reinforcement and an integral part of the cellular structure through surface impregnation. It is sufficient, however, if the coating when applied adheres to the cellular structure, either by chemical or mechanical adhesion, with sufficient tenacity that ordinary handling will not cause parting between the coated surface and the coating. The coating 16 is applied so as to provide sufficient thickness to cover protruding parts of shattered and broken cell walls at the surface of the structure.

The coating provided is tough enough and has sufficient adherence to remain intact and provide an edge fringe about the uncoated working surface, as indicated at 20 in the drawings, as the work surface 15 is worn away during abrading operations. In operation, the fringe 20 forms about the working surface 15 as shown most clearly in Figs. 2, 3 and 4. This fringe varies from a starting length of about $\frac{1}{32}$ inch and may develop to a length of approximately $\frac{1}{8}$ inch as the work surface of the structure wears away during the abrading operations. This fringe provides for keeping debris from the work surface and cuttings from the work piece 22 under the work surface, as indicated at 23 in Figs. 2 and 3, where it serves as an effective cutting medium. Thus, the action of this coating fringe is to prevent the escape of broken cell wall debris out from under the work surface 15 and to keep such debris and cuttings from the work piece 22 under the work surface 15. The action of the fringe may be likened to that of a broom as it sweeps around the edges of the work surface.

A number of coatings have been found to be satisfactory for the purposes of this invention; for example, and among others, rubber base paints, plastic coatings, natural rubber emulsions, many oil-base paints and synthetics. However, a preferred coating which is very suitable comprises a stabilized dispersion of a copolymer of styrene and butadiene having an iodine number of about 140. In the dispersed phase, this coating is composed of microscopic particles of solid styrene-butadiene copolymer, the particles being approximately 0.2 micron in diameter. The particles coalesce as the water evaporates and form a continuous, colorless film having a slight opacity. This coating can also be pigmented and otherwise compounded with thickeners and common paint ingredients before application to the cellular structure if desired. The coatings may be treated with deodorants or odor producing additives such as "cedar" or "pine" oil, which will be released or exposed to volatilization as the abrading article is worn. These additives are desirable where the cellular ceramic structure used is one containing entrapped sulphur gases which are released when the cells are broken during use of the structure as an abrading article.

From the above description and drawings, it will be apparent that in practice a cellular ceramic structure is fabricated to the approximate or exact shape desired to be used as an abrading article or tool. This structure is then coated, leaving one surface thereof free of coating or thereafter removing the coating from an area previously covered to expose a work surface. The structure is then dried or otherwise treated according to common practice to stabilize the coating so as to permit handling and use.

By covering and supporting shattered and broken cell walls, the coating keeps these surface fragments from being further broken and separated from the structure during ordinary handling and use. The coating also per-

mits handling the structure without tearing and abrading the skin of the operator's hands, as well as making it possible to utilize cellular ceramic structures of greater fragility and hence greater potential abrading ability than would be possible without the coating. Coating also prevents the wear, handling disintegration and clipping from the cutting tool as it leaves or enters the structure when fabricating the abrading article to a desired shape, which uncoated cellular ceramic structures are subject to.

10 The coating fringe, which develops about the work surface as the structure wears away during abrading operations, keeps the debris and cuttings under the work surface and on flat work pieces, provides for approximately double the amount of abrasion obtained from an 15 uncoated structure under comparable conditions. The cushioning effect and support given to the structure by the coating also contributes to the work life of the abrading article by permitting the striking of an edge to clean 20 a clogged work surface by jarring debris and cuttings therefrom.

While the invention disclosed herein is of primary importance in the application thereof to abrasive articles formed from cellular ceramic structures, it is to be understood that the principles of the invention can be applied to other articles and devices. Application of the invention to other types of structures can also be readily effected by those skilled in the art to which this invention relates.

Having thus described the invention, what is claimed 30 as new and desired to be secured by Letters Patent is:

1. An abrading article formed from a fragile multi-cellular ceramic structure coated with a compound comprising a stabilized dispersion of a copolymer of styrene and butadiene.

35 2. A coating for a fragile multi-cellular ceramic abrading structure comprising a flexible coating substance adhering to the outer surface thereof which as the ceramic structure wears develops a fringe surrounding a work surface produced on said abrading article, said fringe 40 projecting from each edge of the work surface and providing for retaining particles broken from said ceramic structure in contact with the work surface.

3. An abrading article formed from a fragile multi-cellular ceramic structure having a work surface and having a flexible coating reinforcing the outer surface of said abrading article adjacent to said work surface and forming a fringe around the edge of the work surface, said fringe projecting from each edge of the work surface and providing for retaining particles broken from 45 said ceramic structure in contact with the work surface.

4. A coating for a cellular ceramic abrading structure having a work surface comprising a flexible material surrounding said abrading structure and bonded to the surface thereof to form a sheath for the abrading structure and which as the abrading material wears forms a fringe 55 extending around the outer edges of said work surface whereby debris from the wearing away of the work surface is collected and held in contact with the work surface by said fringe.

5. In combination, a cellular ceramic block structure 60 having a plurality of sides, a flexible coating adhered to some but not to all of said sides and composed of a material which abrades more slowly than the ceramic structure and which as the ceramic structure wears forms a flexible fringe which holds broken particles of the ceramic structure and other debris within the confines of said fringe.
